UNITED STATES PATENT OFFICE.

ALBERT C. WILLIS, OF COLUMBUS, OHIO.

CHURN.

SPECIFICATION forming part of Letters Patent No. 761,121, dated May 31, 1904.

Application filed January 4, 1904. Serial No. 187,678. (No model.)

To all whom it may concern:

Be it known that I, ALBERT C. WILLIS, a citizen of the United States, residing at Columbus, in the county of Franklin and State of Ohio, 5 have invented a new and useful Churn, of which the following is a specification.

My invention relates to churning, and especially to the churn-dasher, having for its objects to produce a comparatively simple inexpensive device of this character which in practice will efficiently perform its functions and cause a thorough agitation of the cream, thereby rapidly converting the latter into butter.

To these ends the invention comprises the 15 novel features of construction and combination of parts more fully hereinafter described.

In the accompanying drawings, Figure 1 is a vertical longitudinal section through a churn having my improved dasher applied thereto. 20 Fig. 2 is a top plan view of the dasher. Fig. 3 is a detail sectional elevation of the lower portion of the same. Fig. 4 is a bottom plan view of the same.

Referring to the drawings, 1 designates the 25 churn vessel or body seated upon a base 2, having an upstanding flange engaging the bottom of the vessel, which is provided with a discharge-opening 3 and upon its interior with radiating deflecting-wings 4. Bolted or 30 otherwise secured to the base is a substantially U-shaped vertical frame presenting a pair of oppositely-disposed vertical standards 5 and a top connecting-bar 6, carrying a depending bracket or hanger 7, horizontally perforated 35 adjacent to its lower end to constitute a bearing-opening which is in alignment with a similar bearing-opening provided in one of the standards 5, there being journaled for rotation in said bearings a horizontal counter- 40 shaft 8, carrying at its outer end a fly-wheel 9, at its inner end a bevel-gear 10, and between its ends a spur-pinion 11. The pinion 11 is in mesh with a driving-gear 12, fixed upon a drive-shaft 13, journaled in a suitable 45 bearing with which the standard 5 is provided, there being fixed upon the outer end of said shaft an operating-wheel 14. The bevel-gear 10 is in mesh with a bevel-pinion 15, fixed upon a vertical dasher-shaft 16, disposed at the center of the churn and having

bearings for rotation at its lower end in a step 17, provided at the bottom of the vessel, and at its upper end in a suitable bearing provided at the center of the connecting-bar 6. These parts may all be of any suitable or preferred construction and material, inasmuch as they constitute no part of my invention. 55

Mounted upon the shaft 16 and adjustable longitudinally thereof by means of a set-screw 18 is the dasher 19, constituting the subject of 60 the present invention, said dasher comprising a central shaft-receiving sleeve 20, horizontal radiating blades 21, and a jacket or casing 22. The sleeve 20, which is of tubular form, has fixed to and carries at its lower end the blades 65 21, which unite at their inner ends and radiate from the sleeve in a substantially horizontal plane. The blades, which from their inner toward their outer ends curve backward relative to the direction of rotation of the 70 dasher indicated by the arrow in Fig. 2, are also curved slightly downward between their ends and have their lower faces inclined downward from front to rear in transverse section. Thus as the blades rotate they sweep 75 the cream from the center outward and also create a downward suction, thereby causing a downward current or flow of the cream within the casing 22.

The casing 22, which is composed, preferably, of sheet metal bent or folded at its upper end around a strengthening ring or band 23 and soldered or otherwise secured at its lower end to the outer ends of the blades 21, is preferably of the form herein shown, having a substantially vertical cylindrical lower portion 24 and an upper conical or tapered portion 25, the upper and lower ends of the casing being open to permit free passage of the cream vertically therethrough. Formed 80 through the wall of the upper conical portion of the casing is a series of inlet-openings 26, disposed, respectively, vertically above the blades 21, while a series of outlet-openings 27 are formed through the wall of the lower cylindrical portion at points respectively between the blades. 85 90 95

In practice operation of the wheel 14 causes, through the medium of the intermediate gearing, a forward rotation of the shaft 16 and 100

the dasher 19 carried thereby. As the dasher rotates the downward suction created by the blades 21, as heretofore explained, serves to draw currents of the liquid downward through 5 the inlet-openings 26 and an outflow of liquid through the outlet-openings 27, while at the same time a rotary or whirling motion is imparted to the entire body of liquid. Thus a thorough agitation of the cream is established 10 and maintained, thereby rapidly converting the same into butter, attention being directed to the fact that in its passage through the inlet-openings 26 the cream is divided into distinct streams whereby a more thorough separation and breaking up of the particles is attained, with a consequent facilitation of the process of conversion of the cream and saving of time in the churning operation.

From the foregoing it will be seen that I 20 produce a simple inexpensive device which is admirably adapted for the attainment of the ends in view; but it is to be understood that I do not limit myself to the precise details

herein set forth, inasmuch as minor changes may be made therein without departing from 25 the spirit of the invention.

Having thus described the invention, what is claimed is—

In a churn-dasher, the combination with a series of substantially horizontal radiating 30 blades adapted to produce a downward suction, of a shell or casing around and fixed for rotation with the blades, said casing having an upper inwardly-converging portion provided with inlet-openings disposed respectively vertically above the blades and a lower substantially vertical portion having outlet-openings disposed between the blades.

In testimony that I claim the foregoing as my own I have hereto affixed my signature in 40 the presence of two witnesses.

ALBERT C. WILLIS.
